UNITED STATES PATENT OFFICE.

ANDERS AUNE, OF WALTHAM, MASSACHUSETTS.

STEM-WINDING WATCH.

SPECIFICATION forming part of Letters Patent No. 723,123, dated March 17, 1903.

Application filed June 2, 1902. Serial No. 109,834. (No model.)

To all whom it may concern:

Be it known that I, ANDERS AUNE, of Waltham, in the county of Middlesex and State of Massachusetts, have invented certain new and useful Improvements in Watch-Setting Attachments, of which the following is a specification.

This invention relates to stem-winding mechanism for watches, and has for its object the production of a simple, compact, and ornamental mechanism, all the parts of which may be mounted upon one side of the front plate of the watch-movement and which will provide for positively holding the clutch when in gear with the setting-train, so that if any member of the latter should be tight there will be no liability of the resulting friction causing a slipping of the clutch.

To these ends the invention consists in the construction and combination of parts substantially as hereinafter described and claimed.

In the drawings, Figure 1 represents a plan of my improved mechanism and of so much of a watch-movement as is necessary to illustrate the adaptability and the operation of the invention, the parts being in position for setting. Fig. 2 represents a similar view with the parts in position for winding.

Similar reference characters indicate similar parts in both the figures.

The front plate of the watch-movement is indicated at *a*, and said plate supports the winding and setting mechanism, as hereinafter described. The arbor *b*, having a square portion *b'* for the sleeve, is provided with the usual crown *c* and has its inner end or head *b²* adapted to operate the sleeve-shifting mechanism, as will presently appear. The pinion *d* for the winding-train is indicated at *d* and is provided with teeth *d'*, adapted to mesh with the teeth *e'* at the outer end of the sleeve *e*, said sleeve having teeth *e²* at its inner end and a peripheral groove *e³*.

All of the parts so far described are or may be of an ordinary construction, as indicated in the drawings.

It is to be understood that in practice the arbor *b* will be suitably supported in a bearing, such as two half-bearings formed by oppositely-arranged grooves in the pillar and

top plates. As such arrangement forms no part of the present invention, I have omitted an illustration of it in order that the parts which do embody my invention and which will now be described may appear more clearly in the drawings.

A lever *g*, pivoted at *g'* to the front plate, has its inner end *g²* projecting into the path of movement of the end or head *b²* of the arbor and has its outer end *g³* formed with a preferably curved surface, as indicated, said lever having also a shoulder *g⁴*. A spring *h* is secured by means of a screw *h'* to the front plate *a* and is preferably steadied in position by means such as a dowel-pin. The outer or free end of the spring bears against the shoulder *g⁴* of the lever *g* and normally acts to hold the lever *g* in the position shown in Fig. 1. A sleeve-operating lever *i* is pivoted to the plate *a* at *i'* and has its longer end entering the peripheral groove *e³* of the sleeve. This lever *i* is located in a recess *f*, formed in the plate *a*, said recess being of such a depth that the lever *i* will be substantially flush with the said plate *a*, so that all the parts will occupy a very small space. Secured to said lever *i*, as by a screw *k'* and a suitable dowel-pin, is a spring *k*, having its intermediate portion curved or bent, so that no contact will be made with the end of the lever *g* excepting at the fixed and free ends of said spring *k*. The fixed end of the spring *k* is formed to present an abutment *k²* for the end of the lever *g*, and adjacent to said abutment is a cam-surface *k³*. When the crown is pushed inward so that the end or head *b²* swings the lever *g* to the position shown in Fig. 2, the outer end of said lever *g* engages the free end of the spring *k*, and through said spring *k* yieldingly moves the sleeve-operating lever *i*, so as to slide the sleeve into position where its outer teeth *e'* will engage the teeth *d'* of the pinion *d*. When the parts are in this position and the arbor is being rotated backward, the spring *k* permits the lever *i* to yield with the sliding movements of the sleeve-clutch. Upon pulling the arbor outward the spring *h* causes the lever *g* to swing, so that its end *g²* follows the movement of the arbor, and the outer end *g³* of said lever *g* is carried from the position shown in Fig.

2 to the position shown in Fig. 1, its outer end acting against the cam-surface k^3 , and consequently oscillating the lever i , and finally coming to a stop behind the abutment 5 k^2 , entirely leaving the free end of the spring k . The swinging of the lever i throws the sleeve to a position so as to disengage it from the teeth of the pinion d of the winding-frame, and carries the teeth e^2 of said sleeve into 10 engagement with the teeth of one of the pinions of the setting-train in the usual manner. Since the outer end of the lever g is opposite the abutment k^2 , which, as above stated, is fixed on the lever i , the said lever i is held 15 positively in the position shown in Fig. 1, so that if any member of the setting-train tends to catch or stick the resistance afforded thereby cannot cause a slipping of the clutch-teeth e^2 , for the reason that the sleeve e is held 20 firmly by said lever i .

Having now described my invention and set forth one embodiment thereof, I wish it to be understood that I do not limit myself to the specific construction illustrated and 25 described, as the same may be modified to

more or less extent without departing from the spirit of my invention.

I claim—

A stem winding and setting mechanism for watches, comprising a longitudinally-movable 30 stem-arbor, a sleeve-clutch thereon adapted to alternately engage the winding and setting trains, the lever g having one end in the path of movement of the stem-arbor, and having a shoulder g^4 between its end and the pivot, the 35 lever i engaging the sleeve-clutch to reciprocate it and provided with an abutment and an adjoining cam-surface to be engaged by the adjacent end of the lever g , said lever i being provided with a spring extending from the 40 abutment to the opposite side of the pivot and adapted to be engaged by the end of the lever g alternately with the engagement with said abutment.

In testimony whereof I have affixed my signature in presence of two witnesses.

ANDERS AUNE.
